United States Patent

Des. 240,739
Patented July 27, 1976

240,739

TELEPHONE

Douglas P. Montague, Chicago, and Howard J. Morrison, Deerfield, Ill., assignors to Marvin Glass & Associates, Chicago, Ill.

Filed Oct. 20, 1975, Ser. No. 623,813

Term of patent 14 years

Int. Cl. D14—03

U.S. Cl. D26—14 A

Fig 1

Fig 4

Fig 5

Fig 2

Fig 3

FIG. 1 is a perspective view of a telephone embodying our new design;

FIG. 2 is a top plan view thereof;

FIG. 3 is a side elevational view thereof, the opposite side being substantially identical thereto;

FIG. 4 is an end elevational view thereof, the opposite end being substantially identical thereto; and

FIG. 5 is a bottom plan view thereof.

We claim:

The ornamental design for a telephone, as shown and described.
